UNITED STATES PATENT OFFICE.

DAVID G. BLATTNER, OF BOGOTA, NEW JERSEY, ASSIGNOR TO WESTERN ELECTRIC COMPANY, INCORPORATED, OF NEW YORK, N. Y., A CORPORATION OF NEW YORK.

APPARATUS FOR THE VISUAL INTERPRETATION OF SPEECH AND MUSIC.

Application filed October 6, 1925. Serial No. 60,716.

This invention relates to apparatus for the visual interpretation of acoustic effects such as are derived from electrical sound reproducing systems.

5 An object of the invention is to facilitate the interpretation of speech and music with the aid of electrical illumination.

A related object of the invention is to produce lighting effects which blend in harmony with the articulate sounds produced 10 by a phonograph or other sound reproducing system.

The invention provides means for accentuating the artistic effect produced by musical 15 and other programs whose themes suggest various degrees of light and color. The invention may be employed, for example, in systems of the type disclosed and claimed in a copending application of E. B. Craft, 20 Serial No. 60,715, filed October 6, 1925, in which a portion of the energy in an electrical sound reproducing system is utilized to produce complementary tones and shades of light and color.

25 In the system disclosed in the Craft application, the illumination produced by a plurality of colored lamps is varied in accordance with the characteristic frequencies and intensities of the sound wave energy in such 30 a way that a variation in intensity of the light from a maximum brilliancy to complete darkness may be obtained according to the sound produced. According to a feature of the present invention, means are provided 35 for controlling the light produced in such a system in such a way that the illumination will never fall below a predetermined minimum intensity.

The various features and advantages of 40 the invention will appear from the following description and the accompanying drawing, in which:

Fig. 1 is a circuit diagram of a phonograph reproducing system embodying the invention.

45 Fig. 2 is a perspective view of a cabinet phonograph equipped in accordance with the invention.

In Fig. 1, a phonograph reproducer 5 is 50 coupled through a transformer 6 to an amplifier 7, the output of which is coupled through a second transformer 8 and circuit 9 to an electrically operated loud speaker 10.

The reproducer 5 may be of any suitable

type, such as the electromagnetic reproducer 55 disclosed and claimed in a copending application of H. C. Harrison, Serial No. 66,624, filed November 3, 1925. The reproducer 5, when actuated by a phonograph record, as illustrated, generates electrical currents 60 which drive an electromagnetic motor element of the loud speaker 10 of any well known construction in accordance with the record. The volume level of the reproduced speech or music may be controlled in any 65 well-known manner, as by adjusting the amplifier 7 to control the electrical input to the loud speaker.

A plurality of channels, including wave 70 filters F_1 , F_2 and F_3 , respectively, are associated with the circuit 9. The output side of the filter F_1 is coupled to an amplifying detector A_1 , which may be of the space discharge type, having an incandescent lamp L_1 connected in its output circuit. Similarly, 75 detector A_2 and lamp L_2 are connected in circuit with the filter F_2 , and detector A_3 and lamp L_3 are connected in circuit with filter F_3 .

The several wave filters employed in the 80 system are designed to freely transmit a pre-assigned range of frequencies and to effectively suppress all frequencies lying outside of such range. Filter F_1 , for example, may be a low pass filter transmitting all frequencies from zero to 410 cycles, and suppressing all other frequencies. Filter F_2 may be of the band pass type, designed to transmit frequencies of 410 to 820 cycles, and filter F_3 may be a high pass filter transmitting all 85 frequencies above 800 cycles. These filters may be designed in accordance with the principles set forth in the U. S. patent to Campbell No. 1,227,113, issued May 22, 1917.

The generator G and rectifier 11 constitute 90 a common source of space current and filament heating current for the amplifying detectors A_1 , A_2 and A_3 , and also serve to supply energy to the lamps L_1 , L_2 and L_3 . A grid polarizing battery 12 is connected 100 in common to the cathodes of the several detector tubes.

In operation, a small portion of the energy in the circuit 9 of the loud speaker will be selectively transmitted by one or more of 105 the filters F_1 , F_2 and F_3 , to the input circuits of the respective detectors, depending upon the frequency and intensity of the trans-

mitted energy. The energy thus impressed upon the input circuit of any detector will cause an increase in the space current in the associated output circuit, thus lighting the associated lamp to a brilliancy depending upon the intensity of the received energy.

According to a feature of the invention, an auxiliary circuit is provided for lighting the lamps L_1 , L_2 and L_3 to a predetermined 10 minimum brilliancy. As illustrated, the resistance elements R_1 , R_2 and R_3 are connected in series with the common source of space current and in parallel with the anodes of the respective space discharge devices A_1 , A_2 and A_3 , thus forming a plurality of closed loop circuits, each of which includes the common source of space current supply, a lamp and the associated resistance element. The lamp L_1 , for example, is normally energized over a circuit including the rectifier 11, the filament of lamp L_1 , and resistance element R_1 , thus causing this lamp to glow to a predetermined intensity when no energy is supplied from the circuit 9 to the channel including the filter F_1 . The lamps L_2 and L_3 are caused to glow in a similar manner. When energy from the circuit 9 is transmitted to a given channel, however, space current will flow in the 30 associated detector circuit to establish a low impedance path for the respective lamp.

It will be seen from the above that the intensity of illumination may be varied in insensible gradations from a minimum to a maximum brilliancy in harmony with the sound variations produced by the loud speaker 10. If desired, the lamp L_1 , which is controlled by the lower frequencies, may be colored red, while the lamp L_2 , controlled 40 by the intermediate frequencies, may be colored green, and the lamp L_3 , controlled by the higher frequencies, may be blue. These particular colors are arbitrarily associated with the various frequency bands, but a 45 definite relation may, of course, be established in keeping with the use to which the invention is put. A greater variety of color tones may also be obtained by employing a greater number of channels and differently 50 colored lamps.

In Fig. 2 a plurality of electric lamps, each controlled by a predetermined band of frequencies, are clustered together inside an opalescent bowl 13 mounted on a cabinet phonograph 14. The lamps may also be 55 mounted in many other artistic arrange-

ments either with or without a diffusing screen.

The invention is, of course, susceptible of various other modifications not specifically referred to but included within the scope of the appended claims.

What is claimed is:

1. In a system for visual interpretation of acoustical effects in combination, a source 65 for generating sound wave frequencies, a sound reproducer, a circuit operatively associating the sound reproducer with the sound wave generator, a plurality of lamps associated with the circuit and selectively responsive to intensity and frequency of currents in said circuit, and means for limiting the minimum intensity of the light from the lamps.

2. In a system according to claim 1, auxiliary means for lighting the lamps to a predetermined minimum brilliancy.

3. In a system for visual interpretation of acoustical effects in combination, a source 80 of sound wave frequencies, a sound reproducer, a circuit operatively associating the source of sound wave frequencies and the sound reproducer, a plurality of lamps, a detector for each lamp having its output circuit associated with the lamp and its input 85 associated with the circuit connecting the source of sound wave frequencies and the sound reproducer, and auxiliary means for continually supplying current to the lamps.

4. In a system for the visual interpretation of acoustical effects in combination, a source of sound wave frequency, a sound reproducer, a circuit connecting said source with said reproducer, a plurality of space discharge devices having their inputs associated with said circuit, a source of light individual to each of the space discharge devices, a resistance individual to each of said lights, and a source of space current common to said lights, resistances and space 95 discharge devices.

5. In a system according to claim 4 in which the light sources are included in series with the outputs of the space discharge devices and the common source of current and resistances are included in shunt of the lights.

In witness whereof, I hereunto subscribe my name this 5th day of October A. D., 1925.

DAVID G. BLATTNER.
